UNIFORM JACKET

Adolph Ostwald, Staten Island, N.Y.

Application February 27, 1958, Serial No. 49,825

Term of patent 14 years

(Cl. D3—5)

The figure is a front view of a uniform jacket showing my new design.

The essential feature of the design is that part shown in full lines. The back of the jacket is conventional in appearance.

I claim:

The ornamental design for a uniform jacket, as shown and described.
